UNITED STATES PATENT OFFICE

NINA ARNOLD, OF NEW YORK, N. Y.

DESIGN FOR A PILLOW

Application filed October 23, 1930. Serial No. 37,362. Term of patent 3½ years.

To all whom it may concern:

Be it known that I, NINA ARNOLD, a citizen of the United States, and a resident of the borough of Manhattan, city, county, and State of New York, have invented a new, original, and ornamental Design for Pillow, of which the following is a specification, reference being had to the accompanying drawings, forming a part thereof.

In the drawings, Figure 1 is a front elevational view, and Fig. 2 is a side view.

I claim:

The ornamental design for a pillow, as shown.

NINA ARNOLD.
